UNITED STATES PATENT OFFICE.

JOHN GIBBONS, OF WEST TROY, NEW YORK, ASSIGNOR TO THE UNION
HARDWARE MANUFACTURING COMPANY, OF SAME PLACE.

FASTENING DEVICE FOR HALTERS.

SPECIFICATION forming part of Letters Patent No. 278,931, dated June 5, 1883.

Application filed February 26, 1883. (No model.)

To all whom it may concern:

Be it known that I, JOHN GIBBONS, of the village of West Troy, county of Albany, and State of New York, have invented a new and 5 useful Improvement in Fastening Devices for Halters, of which the following is a specification.

My invention relates to that class of devices that are used in halters to adjustably secure 10 the rope which forms the loop or lead, so that the size of the latter may be varied.

My invention consists, as will hereinafter be more fully described, in the combination of an eye on the end of the rope, through which eye 15 the tether end of the rope is passed to form the lead or loop, and a connected ring and hook, through which ring, near the eye end of the rope, the latter is passed, with the hook adapted to receive and hold the rope near where 20 passed through the eye, and thus secure it to prevent its slipping through the eye.

Accompanying this specification, and forming a part of it, there are two plates of drawings, containing three figures illustrating my 25 invention, with the same designation of parts by letter-reference used in all of them.

Figure 1 in perspective shows the lead or loop as formed with the tether end passed through the eye. Fig. 2 illustrates in another 30 perspective the parts in the same position as shown in Fig. 1, but with the rope secured in the staying-hook. Fig. 3 illustrates in perspective a completed halter containing my improvement.

35 The parts of a halter and those constituting my invention are designated by letter-reference and their function explained as follows:

The letter R indicates the rope from which

the nose loop or lead is formed, and R' that from which the neck-loop is made; E, an eye 40 on the end of the rope from which the lead or nose-loop is formed, and T the tether end of the rope.

The letter B designates a ring, and H an off-set-hook, attached to the side of the ring, the 45 latter surrounding the rope R near its eye end. As thus made, when the rope R is passed through the eye E to form the nose or lead loop, and it is desired to secure the rope to prevent its slipping through the eye, so as to reduce 50 the size of the nose loop or lead, the rope is, where opposite the hook H, passed into the latter to secure it with the parts in the position as shown at Figs. 2 and 3 of the drawings. As thus made and combined with the eye end 55 of a halter, the ring E and hook H make a substantial means for forming and securing the lead or nose loop of a halter that is easily attached and detached. As thus constructed, a very simple and efficient means of securing the 60 loop is produced, and one that is easily connected and disconnected.

Having thus described my invention, what I claim, and desire to secure by Letters Patent, is—

65 The combination of the eye having a split socket with the ring provided with hook, substantially as described, and for the purpose set forth.

Signed at Troy, New York, this 22d day of 70 February, 1883.

JOHN GIBBONS.
